CLAIM

We claim the ornamental design for a dispenser, as shown and described.

DESCRIPTION

FIG. 1 is a bottom perspective view of a dispenser showing my new design;

FIG. 2 is a top perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof;

FIG. 8 is a bottom view thereof; and,

FIG. 9 is a cross-sectional view taken in the direction of line 9-9 in FIG. 8.

The broken lines in the drawings illustrate the portions of the dispenser that form no part of the claim.

1 Claim, 9 Drawing Sheets(56)
